UNITED STATES PATENT OFFICE.

JOHN ESTES EVERETT AND THOMAS RUSSELL EVERETT, OF COCHRAN, GEORGIA.

INTERNAL-COMBUSTION ENGINE.

1,405,403.

Specification of Letters Patent.

Patented Feb. 7, 1922.

Application filed June 24, 1920. Serial No. 391,361.

To all whom it may concern:

Be it known that we, JOHN ESTES EVERETT and THOMAS RUSSELL EVERETT, citizens of the United States, and residents of 5 Cochran, in the county of Bleckley and State of Georgia, have invented certain new and useful Improvements in Internal-Combustion Engines, of which the following is a specification.

10 Our invention relates to internal combustion engines of the four cycle type, and the purpose of our invention is the provision of an engine in which deterioration from wear of the work cylinder and work 15 piston is materially reduced by the employment of means to receive the sideward thrusts generated in the transformation of the reciprocating motion into rotary motion, and to relieve the work cylinder and 20 piston of all duty except that of performing the operations of the cycle whereby, troubles resulting from leakage past the piston is eliminated and the motor remains in 25 perfect operating condition for an indefinite time. It is also a purpose of our invention to produce a high speed engine having a long stroke but short connecting rods.

We will describe one form of internal combustion engine embodying our invention and 30 will then point out the novel features thereof in claims.

In the accompanying drawings:

Figure 1 is a view showing in vertical section one form of engine embodying our 35 invention.

Figure 2 is a plan view of the engine shown in Figure 1 with the cylinder at the upper end of the figure shown in a section taken on the line 1-1 of Figure 1; the 40 second cylinder being shown in a section taken on the line 2-2 of Figure 1; and the third or lower cylinder being shown in a section taken on the line 3-3 of Figure 1.

Similar reference characters refer to 45 similar parts in each of the views.

Referring specifically to the drawings and particularly to Figure 2, we have here shown the engine consisting of only three cylinders in order to simplify the drawings, 50 it being understood that the engine may be formed with any number of cylinders without departing from the spirit of the invention. As shown in Figure 1, the engine comprises a main block casting designated 55 at B and including a plurality of cylinders designated at C, each of which is closed at

its upper end by a cylinder head H of conventional form. Arranged within each of the cylinders C is a work cylinder designated at W which is preferably machined 60 and pressed into place into the block casting and held in position by the coacting projections 15 formed on the confronting sides of the cylinder C and the cylinder W. The cylinder W extends approximately about 65 one-half of the length of the cylinder C, its lower end being open and in communication with the main cylinder C. Working within the cylinder W is a piston P provided with the usual rings and having formed integral 70 therewith a piston rod 16.

As shown in Figure 1, the lower end of the block casting B supports the main bearings in which works a crank shaft S of usual construction, and has secured thereto a crank 75 case K housing said shaft. The crank shaft S carries a plurality of connecting rods R corresponding in number to the number of cylinders C. These connecting rods are operatively connected at their upper 80 ends to secondary or bearing pistons designated at P', one piston for each of the cylinders C. As shown in Figure 1, and the section 2-2 of Figure 2, each bearing piston P' comprises a cross head 17, the under 85 side of which is provided with a socket 17^a into which extends the upper end of the corresponding connecting rod R. The rod R is pivotally secured within the socket 17^a by means of a wrist pin 18 which extends 90 through suitable openings formed in the cross head and connecting rod. The wrist pin 18 is surrounded by a bushing 19 which as shown in Figure 2 is embraced by the upper end of the connecting rod. The opposite ends of the cross heads 17 are formed with arcuate heads 20 to which are secured in any suitable manner arcuate bearing plates 21. The bearing plates 21 contact at 95 all times with stationary bearing plates 22 secured at diametrically opposite points within the cylinder C. These bearing plates are made of suitable bearing alloys and are interchangeable.

The bearing piston P' is operatively connected to the work piston P through the medium of the piston rod 16, the lower end of the latter being pivotally secured between a pair of spaced ears 23 formed on the cross head 17 by a wrist pin 24, which as shown in 100 Figures 1 and 2 is partially embraced by a bushing 25. This manner of connecting the

two pistons permits of entire freedom of the work piston P from flapping of the bearing piston P' when latter has become worn after long usage. The mounting of the 5 wrist pin 24 between spaced ears 23 permits of proper lubrication thereof.

The intake and exhaust manifolds of the engine are indicated at M and M', respectively, and are connected to the upper ends 10 of the cylinders W in the usual manner. The passage of the gases through the manifolds is controlled by poppet valves V actuated in the usual manner.

The operation of the engine is as follows: 15 During the working stroke of one piston P within a corresponding cylinder W, power therefrom is transmitted to the crank shaft S through the medium of the piston rod 16, the wrist pin 24, the cross head 17 20 and the connecting rod R. During this movement of the piston P, a corresponding motion is also imparted to the corresponding bearing piston P' thus causing the latter to move longitudinally and over the stationary bearing plates 22. In this operation 25 of the work piston P, the existing lateral or sideward forces acting upon the piston P' at its point of connection with the connecting rod R is transmitted directly to the bearing plates 21 and 22 so that the working piston P is relieved of such lateral forces and is thus free to at all times perform a true rectilinear movement and to thus cause a uniform wearing of the contacting walls 30 of the work cylinder and work piston so as to prevent leakage past the piston as a result of the irregular wear caused as a result of these lateral forces acting upon the work piston. The same is true for all four 35 strokes.

It is to be particularly noted that the stationary bearing plates 22 have their upper ends disposed in overlapped relation with respect to the lower end of the work cylinder 40 W. This arrangement permits the use of a relatively long cylinder to produce a long stroke without materially increasing the total height of the motor. It also permits of a greater bearing surface for the bearing piston P' than is possible where the diameter 45 of the work cylinder W is the same as that of the cylinder C. Another advantage of this arrangement is the fact that the bearing plates 22 and 23 are removed a sufficient distance from the explosive end of 50 the cylinder W so as not to be detrimentally affected by the heat from the explosions.

By referring to Figure 1, it will be seen that we have provided a relatively short 55 piston rod 16 and a comparatively short connecting rod R. This obviously decreases the angle between the connecting rod and the piston P' which would ordinarily create greater lateral thrusts and thus effect a 60 quicker and more irregular wear of the walls

of the work cylinder. However, by providing the bearing surfaces for the bearing piston P' and arranging the latter so that all lateral thrusts are directed to such piston, this reduction in length of the connecting 70 rod is rendered possible without injury to the work cylinder or work piston.

Although we have herein shown and described only one form of internal combustion engine embodying our invention, it is 75 to be understood that various changes and modifications may be made herein without departing from the spirit of the invention and the spirit and scope of the appended 80 claims.

What we claim is:

1. An internal combustion engine comprising, a main cylinder, a work cylinder arranged concentrically within the main cylinder, a work piston within the work cylinder, bearing plates secured to the inner wall of the main cylinder and disposed in overlapped relation with respect to the work cylinder, a bearing piston movable over said bearing plates and operatively connected to the work piston, a crank shaft, and a connecting rod operatively connecting said bearing piston to said crank shaft. 90

2. An internal combustion engine comprising, a main cylinder, a work cylinder in the upper end of the main cylinder and disposed concentrically thereof, a work piston within the cylinder, bearing plates secured to the inner wall of the main cylinder and disposed in overlapped relation with respect to the work cylinder, a bearing piston movable over the bearing plates pivotally connected to the work piston, a crank shaft, and a connecting rod operatively connecting the bearing piston with said crank shaft. 100

3. An internal combustion engine comprising, a main cylinder, a work cylinder arranged concentrically within the main cylinder at the upper end thereof, bearing plates secured to the inner wall of the main cylinder and disposed in overlapped relation with respect to the work cylinder, a work piston within the work cylinder, a piston rod formed integral with said work piston, 110 a bearing piston comprising a cross head, arcuate heads formed on the opposite ends of said cross heads, ears formed on the upper side of the cross head and receiving said piston rod therebetween, a wrist pin extending through said ears for pivotally connecting the piston rod with said cross head for permitting freedom of the work piston from flapping of the bearing piston, bearing plates secured to said heads and contacting with 115 the first bearing plates, a crank shaft, and a connecting rod pivotally connected to said cross head and to said crank shaft. 120

4. An internal combustion engine comprising, a main cylinder, a work cylinder 130

within the upper end of the main cylinder and disposed concentrically thereof, a work piston within the work cylinder, a cross head movable in the main cylinder and pivotally connected to said piston, a crank shaft, a connecting rod operatively connecting said crank shaft with said cross head, heads formed on the opposite ends of said cross head, bearing plates secured to said

heads, and other bearing plates secured to 10 the walls of the main cylinder and engageable with the first bearing plates, said heads and said bearing plates being so disposed as to receive the lateral thrusts imparted to said cross head as a result of the connection be- 15 tween the cross head and the crank shaft.

JOHN ESTES EVERETT.
